UNITED STATES PATENT OFFICE.

ERNEST K. PETERS, OF FRESNO, CALIFORNIA.

MERCURY CONDENSER.

Application filed January 10, 1927. Serial No. 160,191.

This invention relates to improvements in dental laboratory apparatus, my principal object being to provide a furnace for carrying out the process set forth in my Patent No. 1,589,552, dated June 22nd, 1926; in connection with a condenser for collecting the mercury liberated from the amalgam with the heat treatment of the latter for the purpose set forth in said patent.

10 A further object of the invention is to produce a simple and inexpensive device and yet one which will be exceedingly effective for the purpose for which it is designed.

These objects I accomplish by means of 15 such structure and relative arrangement of parts as will fully appear by a perusal of the following specification and claims.

In the drawings similar characters of reference indicate corresponding parts in the 20 several views:

Fig. 1 is a side view of my improved furnace and condenser, the former mainly an exterior elevation and the latter in section.

Fig. 2 is a plan view of a support or pan 25 for the amalgam to be treated.

Fig. 3 is a plan view of one form of condenser baffle-disc.

Fig. 4 is a similar view of the other or alternate form of baffle-disc.

30 Referring now more particularly to the characters of reference on the drawings, the furnace comprises a casing 1 converging toward its upper end to unite with a flue 2. The casing has a hinged side door 3 provided with a suitable latch 4, the door itself having an opening 5 therein, preferably of rectangular form. The casing rests on an asbestos plate 6 which has a central opening 7, the plate being fitted in a supporting member 8 having legs 9. A Bunsen burner 10 or the like is placed under the plate 6 so that the flame from the burner will be directed into the furnace casing through the opening 7. The casing rests 35 solidly on the plate 6 so as to prevent the formation of eddy currents from about the bottom rim of the casing.

The flue 2 leads to the top of a condenser which comprises a vertical and preferably 40 circular casing consisting of a cap 11 to which the flue is connected, a main body 12 detachably connected to the cap and a base 13 detachably connected to the body. These 45 members of the condenser when connected together form a substantially air-tight en-

closure. Disposed in the condenser casing is a number of vertically spaced discs 14 preferably having a close fit with the interior of the body 12, and having a number of circumferentially spaced openings 15 therethrough adjacent the rim. Located intermediate the discs 14 in spaced relation thereto are other discs 16 of similar nature having a single central opening 17 therethrough. The discs are all removable and the bottom 50 one (which is of the type 14) has a stem 18 connected thereto which projects upwardly through all the discs so as to enable the same to be withdrawn vertically when the condenser cap is removed.

55 Sponges 19 or other similar porous members or material substantially fill the condenser casing between the discs. The base 13 has a side opening 20 (below the lowermost disc) from which a gas outlet 21 leads to the intake of a suction fan 21 of suitable type. The opening 20 is normally covered by a removable screen 22 of gauze or the like. A water drain passage 23 normally closed by a plug 24 extends outwardly from 60 the bottom of the base 13 and flue 21.

65 Arranged outside the condenser is an atomizer 25 of suitable character, the atomizer pipe 26 from which leads into the flue 2 and terminates in a downwardly facing 70 nozzle 27 disposed to throw a spray into the top of the condenser.

The amalgam to be heat treated, said amalgam being of mercury and gold as set forth in the aforementioned patent, is placed 75 on a support or pan preferably comprising a frame 28 having a wire mesh bottom 29, a handle 30 of suitable length and character projecting outwardly from the frame.

In operation the amalgam member is 80 placed on the pan which is inserted into the furnace through the opening 5 or through the larger opening obtained by opening the door 3. With the operation of the burner 10 an intense heat is had in the furnace 85 which will instantly cause the disassociation of the mercury in the amalgam from the gold, the mercury rising in the form of a gas. By reason of the suction of the fan 21, the 90 gas is drawn from the furnace, through the flue 2 and into the condenser, where it is at once subjected to the cooling influence of the water spray from the atomizer nozzle. This 95 cools the gas and the mercury is condensed out of the same and is deposited in solid 100

form on the sponges. Owing to the vertically spaced discs in the condenser, with their staggered openings, the gas cannot pass directly down to the flue 21 but must follow a zigzag path. This of course retards the flow of the gas and insures that all the mercury content of said gas will be condensed before it has a chance to escape, so that by the time the outlet 21 is reached only gas having no commercial value remains. The uppermost sponges of course tend to receive most of the mercury, so when upon inspection the gauze screen 22 is found to have mercury adhering thereto, it may be taken as a sign that the mercury collecting capacity of the condenser has been reached. The parts of the condenser are then disassembled to enable the sponges to be removed, so that the latter may then be treated in the proper manner for the recovery of their mercury content in concentrated form.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

35 1. A mercury condenser comprising a vertical casing, gas intake and outlet passages at the top and bottom thereof respec-

tively, and sponges substantially filling the casing between the intake and outlet.

2. A mercury condenser comprising a 40 vertical casing, gas intake and outlet passages at the opposite ends thereof, means in the casing between the intake and outlet for catching and retaining any mercury in the gases passing from the intake to the outlet 45 and a removable gauze screen across the outlet at the inception thereof.

3. A mercury condenser comprising a vertical casing, a removable cap for the casing, an intake pipe connected to the cap, removable vertically spaced perforated plates in the casing, and elements to collect and retain mercury removably mounted between and supported by the plates.

4. A mercury condenser comprising a 55 vertical casing, a removable cap for the casing, an intake pipe connected to the cap, removable vertically spaced perforated plates in the casing, means connecting the plates to enable the same to be inserted and removed as a unit and mercury collecting material 60 between the plates.

5. A mercury condenser comprising a vertical casing, gas intake and outlet passages at the opposite ends thereof, a plurality 65 of vertically spaced plates in the casing fitting between the sides, alternate ones of said plates having a central opening and the remainder having openings adjacent their periphery, and mercury collecting material 70 between said plates.

In testimony whereof I affix my signature.

ERNEST K. PETERS.
